(57) **CLAIM**

The ornamental design for a coffret, as shown and described.

DESCRIPTION

FIG. 1 is a perspective view of a coffret in a first position, in accordance with my design;

FIG. 2 is a front view of a coffret shown in FIG. 1;

FIG. 3 is a back view of a coffret shown in FIG. 1;

FIG. 4 is a first side view of a coffret shown in FIG. 1;

FIG. 5 is a second side view of a coffret shown in FIG. 1;

FIG. 6 is a top view of a coffret shown in FIG. 1;

FIG. 7 is a bottom view of a coffret shown in FIG. 1;

FIG. 8 is a perspective view of a coffret in a second position, in accordance with my design;

FIG. 9 is a front view of a coffret shown in FIG. 8;

FIG. 10 is a back view of a coffret shown in FIG. 8;

FIG. 11 is a first side view of a coffret shown in FIG. 8;

FIG. 12 is a second side view of a coffret shown in FIG. 8;

FIG. 13 is a top view of a coffret shown in FIG. 8;

FIG. 14 is a bottom view of a coffret shown in FIG. 8;

FIG. 15 is a perspective view of a coffret in a third position, in accordance with my design;

FIG. 16 is a front view of a coffret shown in FIG. 15;

FIG. 17 is a back view of a coffret shown in FIG. 15;

FIG. 18 is a first side view of a coffret shown in FIG. 15;

FIG. 19 is a second side view of a coffret shown in FIG. 15;

FIG. 20 is a top view of a coffret shown in FIG. 15; and,

FIG. 21 is a bottom view of a coffret shown in FIG. 15.

In the figures, the broken lines, showing portions of a coffret, depict the environment and form no part of the claim.

1 Claim, 21 Drawing Sheets
